UNITED STATES PATENT OFFICE.

J. H. GOOCH, OF OXFORD, NORTH CAROLINA.

IMPROVEMENT IN PLOWS.

Specification forming part of Letters Patent No. **28,169**, dated May 8, 1860.

To all whom it may concern:

Be it known that I, J. H. GOOCH, of Oxford, in the county of Granville and State of North Carolina, have invented a new and useful Improvement in Plows; and I do hereby declare that the following is a full, clear, and exact description of the same, reference being had to the accompanying drawings, forming a part of this specification, in which—

Figure 1 is a rear view of the plow with all the parts attached; Fig. 2, a side view of the plow without the beam and handles; Fig. 3, a side view of the plow with one part of the mold-board detached; Fig. 4, a side view of the plow with two detached parts of the mold-board.

Similar letters of reference in each of the several figures indicate corresponding parts.

The nature of my invention consists in making the mold-board extension in two parts, the dividing-line between the two parts being horizontal, or nearly horizontal, for the purpose of transforming the plow into a cultivator, subsoil, or complete turning plow, by simply detaching either one or both of those two parts.

To enable others skilled in the art to make and use my invention, I will proceed to describe its construction and operation.

The standard L of the plow is fastened to the beam N at M in the usual manner. The handles P O are attached each to one side of the rear end of the beam. The lower end of the landside-handle P rests in a stirrup, R, projecting from the inner surface of the landside K of the plow. The lower end of the other handle, O, is fastened to the handle P, and both are fastened to the landside K by means of a screw, Q, passing through these three parts. The standard is made with a short wing, C, and a foot, D, to which latter a point, E, can be attached. The mold-board extension A B of the plow fits the side edge of the wing C and the upper edge of the foot D, and is attached to the wing C by two or more screws and nuts, X J. The mold-board extension is made in two parts by dividing it on a horizontal, or nearly horizontal, line, $x' x''$, the inner end of which line is slightly curved, as seen at $x' x''$. This horizontal division of the mold-board is for the purpose that the lower piece, A, shall have the proper shape of a half-mold-board plow after the upper piece, B, has been

removed. On leaving the piece B in its place and removing piece A the piece B exhibits the shape and serves the purpose of the mold-board of a subsoil-plow. By attaching the pieces A B to the wing C a complete turning-plow is obtained.

It will be seen that a horizontal, or nearly horizontal, division, as above described, is necessary in order to obtain, by the removal of one or the other of the pieces A B, the proper mold-board outline of a half mold-board or a cultivator-plow. Each of the pieces A B is provided with a flange, G F, which flanges reach underneath and rest against the inside surface of the wing C, and are fastened to the wings by two or more screws, J X.

The drawings represent a new mode of making these or similar plow-fastenings at X Y. The inside surface of the wing C is provided with a dovetail slot, Y, which terminates in that edge of wing C against which rests the edge of piece B. The head of the screw X is made just to fit the dovetail slot, and is introduced from the open end of the slot in the edge of wing C. The piece B is then attached, the hole in the flange F fitting the screw X.

It will be seen that when B is in its place the curvature at $x' x''$ of the horizontal edge of B will prevent the piece from giving way in the direction of the line $x' x''$, and will hold it firmly against the edge of wing C, while the screw X and nut I serve to prevent the piece B from coming off in any other direction. Thus it will be seen that a perfectly secure mode of fastening is obtained.

I do not claim as my invention confining the detachable portions of a mold-board of a plow to its main parts by means of screws and dovetail slots; but

What I do claim as my invention, and desire to secure by Letters Patent, is—

Making the mold-board extension in two parts, A and B, the dividing-line between the two parts A and B being horizontal, or nearly horizontal, for the purpose of transforming the plow into a cultivator, subsoil, or complete turning plow by simply detaching either one or both of those two parts, substantially as set forth.

J. H. GOOCH.
